CRUTCH ARMREST

Henri C. McGowan, Augusta, Ga.

Application March 12, 1945, Serial No. 582,235

5 Claims. (Cl. 135—52)

1

This invention relates to an improved armrest for crutches, and more particularly to an armrest which may be employed in the crutch as initially made, or may be manufactured for application to a crutch having a conventional armrest.

Conventional armrests for crutches are made of the same thickness, or substantially the same thickness throughout, or at least throughout the upper portion thereof on which the body is supported. In some cases, such as those in which the armrest is provided with padding which makes the armrest thicker and bulkier than an unpadded armrest, the central portion of the rest is made slightly narrower than the ends, but the difference is not substantial enough to amount to any departure from armrests having the same thickness throughout. In either case, the armrest may slip or slide backward or forward under the arm or arm pit. This causes unnecessary friction and chafing, and presents the possibility of the crutch slipping from under the arm pit at each step. Such armrests, furthermore, may twist or turn under the arm pit about the vertical axis of the crutch, with the resulting possibility of slipping from beneath the arm. Such twisting and turning also may result in the slipping of the tip of the crutch.

It is desirable that the upper portion of a crutch armrest be smooth so as to minimize friction and chafing as much as possible. The sides of the armrest do not ordinarily move against or rub any portion of the body, and if smooth cannot be securely clamped between the arm and body when the crutch is temporarily unused, as when the grip of the hand on the crutch is released in order to employ the hand for some other purpose. In such cases, it is difficult to move the hand without also moving the upper part of the arm slightly, often causing the crutch to fall to the ground since the smooth sides of the armrest present no frictional surface to aid in retaining the crutch in position. The crutch armrest of this invention avoids these defects and difficulties.

It is an object of this invention to provide a crutch armrest either applicable to a conventional crutch or employed in place of a conventional armrest in the manufacture of a crutch.

It is another object of this invention to provide a crutch armrest which prevents accidental movement of the crutch out of position beneath the arm.

It is a further object of this invention to provide a crutch armrest having a relatively wide

2

upper surface to minimize pain and discomfort to the user of the crutch.

It is also an object of this invention to provide a crutch armrest having enlarged ends to prevent longitudinal shifting of the armrest under the arm pit.

It is an additional object of this invention to provide a crutch armrest having enlargements at the end portions thereof to prevent twisting of the crutch.

It is still another object of the invention to provide a crutch armrest having roughened surfaces on the side portions thereof to facilitate clamping of the crutch between the arm and body.

Other and further objects and advantages of the present invention will be apparent to those skilled in the art from the following description and the appended drawing.

In the drawings:

20 Figure 1 is a view partly in side elevation and partly in section of the armrest of this invention applied to a conventional crutch armrest;

Figure 2 is a bottom view of the armrest of Figure 1;

25 Figure 3 is a vertical cross-sectional view, with parts in elevation, taken on the line III—III of Figure 1;

Figure 4 is a side elevational view of a crutch armrest according to this invention initially included in the manufacture of a crutch; and

30 Figure 5 is a fragmentary plan view of an armrest similar to that of Figure 2, but showing a modified form of the end portion thereof.

The armrest 10 is made substantially wider or 35 thicker than the conventional armrest so that the central portion of the upper surface 11 provides a broad surface under the arm pit. The width of this portion may be of the order of three inches. The sides of the armrest below the 40 surface 11 are provided with corrugations 13 extending horizontally therealong to facilitate gripping the crutch between the arm and body of the wearer. The corrugated surfaces extend over only the lower portions of the sides 12, to avoid 45 any rough surface near the top of the armrest which might cause chafing or discomfort.

The bottom of the armrest 10 is provided with a slot 14 extending longitudinally of the armrest and having a width corresponding to that of a conventional armrest. The top wall of the slot 14, as best shown in Figure 1, has substantially horizontal end portions 14a and a substantially horizontal central portion 14b below the plane of the surfaces 14a with intermediate portions 14c extending at an angle between the ends of the

central portion 14B and the inner ends of the end portions 14a. By this construction, the armrest 10 when applied to a conventional crutch armrest A has at least two points or lines of bearing on the conventional armrest A, and relative rocking movement therebetween is prevented. At least a two-point contact is assured regardless of the curvature of the top surface of the armrest A.

Bolt apertures 15 having counterbores 16 are provided in the sides 12 of the armrest, these apertures extending through the side walls of the slot 14, each aperture being aligned with an aperture in the opposite wall so that a bolt 17 or the like may extend through the aperture to secure the armrest 10 to the conventional armrest A. The conventional armrest A is provided with a plurality of apertures each aligned with a pair of the bolt apertures 15 when the armrest 10 is applied over the armrest A, so that the bolts 17 may extend through the two armrests and hold them in secured relation. The counterbores 16 provide recesses accommodating the bolt heads and nuts so that they will not project beyond the surfaces of the sides 12. The armrest 10 may, of course, be secured to the conventional armrest A otherwise than as just described.

The upper portion of the armrest 10 has the ends thereof enlarged to provide bosses or knobs 18. Each of the knobs 18 is of considerably greater width than the central and lower portions of the armrest, and has any suitable extent longitudinally of the armrest. The edges and corners of the knobs 18 are preferably smoothly rounded, and the junctions between the knobs 18 and the narrower portions of the armrest are also preferably smoothly rounded. The knob 18a illustrated in Figure 5 differs from the knobs 18 best shown in Figure 2 primarily in diverging more sharply or abruptly from the sides 12 of the armrest than do the knobs 18.

In the construction illustrated in Figure 4, the armrest 10 is substantially the same as the armrest illustrated in Figure 1, except that it is formed without the slot 14 and the bolt holes 15, since it is not applied over a conventional crutch armrest, but is secured directly to the vertical members or uprights 19 of a crutch in any suitable manner. It will be obvious that the armrest might be so applied to a crutch either in the original manufacture of the crutch or by removing the conventional armrest of a crutch and substituting the armrest of Figure 4, instead of forming the slotted armrest of Figure 1 and applying it over the conventional armrest as described.

The broad surface of the central part of the armrest of this invention results in a decrease in pressure per unit area of the arm on the armrest, thus reducing and relieving to a great extent the pain and discomfort to the arm, arm pit, and the arm and shoulder muscles of a person who uses crutches. This greater surface area also aids in making the crutch more secure under the arm pit.

The formation of the armrest with the knobs or enlargements at the ends thereof holds the armrest, and therefore the crutch, securely in position in two ways. The knobs act as stops to prevent slipping or sliding of the armrest backward or forward relatively to the arm pit, one knob bearing against the body and arm at the front to prevent rearward movement of the armrest and the other similarly preventing forward movement. The knobs also serve as braces or stops to prevent twisting or turning of the crutch on its vertical axis, any such rotation of the crutch

being resisted by one side or the other of each knob, depending upon the direction in which the rotating force is acting. It will be obvious that the knobs greatly increase the safety and comfort of persons using crutches. The knobs practically prevent the possibility of the crutch slipping backward or forward from under the arm so that the person is left without support on one side, and also prevent rotation of the crutch so that the crutch tip does not twist on the walking surface. Such twisting often causes a crutch to slip or slide, resulting in many accidents. By preventing sliding and twisting of the armrest, also, the knobs minimize chafing at the armpit.

The roughened lower surfaces of the sides of the arm rest greatly minimize the possibility of the crutch slipping from underneath the arm when it is momentarily or temporarily held clamped in an upright position against the body by the upper portion of the arm. Smooth side surfaces on crutch armrests do not provide any friction to assist in maintaining the crutch in position in such cases. In fact, in many instances smoothness of the armrest sides results only in the crutch slipping more quickly and easily the tighter the clamping action of the arm thereon.

The armrest of this invention greatly increases the safety, comfort, and convenience of persons using crutches, either permanently or temporarily, and may readily be applied to old crutches or formed as part of new crutches.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

40. 1. A crutch armrest having an upper central portion, enlarged end portions merging with said upper central portion, and side portions below the central portion provided with horizontal corrugations.
45. 2. An auxiliary armrest for application over a crutch armrest, said auxiliary armrest being wider than said crutch armrest and having a slot opening from its bottom to snugly receive the crutch armrest, the portion of the rest forming the top of the slot having intermediate projections for engaging the top of the crutch armrest to provide at least a two-point bearing contact between said auxiliary armrest and said crutch armrest, means to secure said crutch armrest in said slot, and a knob on each end of said auxiliary armrest.
50. 3. An auxiliary armrest for application over a crutch armrest, said auxiliary armrest being wider than said crutch armrest and having a slot opening from its bottom to snugly receive the crutch armrest, the portion of the rest forming the top of said slot having two horizontal surfaces and intermediate projections on the downwardly facing wall of said slot for engaging the top of the crutch armrest to provide at least a two-point bearing contact between said auxiliary armrest and said crutch armrest, means to secure said crutch armrest in said slot, a knob on each end of said auxiliary armrest, and friction means on the sides of said auxiliary armrest.
55. 4. In combination with a crutch having a conventional armrest, an auxiliary armrest slotted to snugly fit over said conventional armrest, that portion of the auxiliary armrest defining the top of the slot having a plurality of horizontal sur-

faces in different planes making at least a two-point contact with said conventional armrest, the side surfaces of said auxiliary armrest being horizontally corrugated to facilitate holding the crutch between the body and arm of the wearer, and means passing through the sides of said auxiliary armrest and the conventional armrest for securing said auxiliary armrest in place on said crutch.

5. An auxiliary armrest for application over a crutch armrest, said auxiliary armrest having a slot in it opening from its bottom to snugly receive the crutch armrest, the portion of the auxiliary armrest defining the top of said slot having two spaced horizontal end portions lying in the

same plane, and an intermediate portion lying below the plane of said end portions, and inclined portions connecting the end and intermediate portions.
